DESIGN FOR A GAME BOARD

Elmer D. Rose, Bradford, Pa.

Application March 31, 1939, Serial No. 83,949

Term of patent 14 years

To all whom it may concern:

Be it known that I, Elmer D. Rose, a citizen of the United States, residing at Bradford, in the county of McKean and State of Pennsylvania, have invented a new, original, and ornamental Design for a Game Board, of which the following is a specification, reference being had to the accompanying drawing, forming part thereof.

The accompanying drawing is a plan view of the game board showing my design. The game board is of no appreciable thickness.

I claim:

The ornamental design for a game board, as shown and described.

ELMER D. ROSE.
